JACKKNIFE BOOM

Alvin H. Wilkinson, Tulsa, Okla., assignor to Auto Crane Company, Tulsa, Okla., a corporation of Oklahoma
Filed Apr. 5, 1962, Ser. No. 185,381
10 Claims. (Cl. 212—144)

This invention relates to improvements in cranes and more particularly, but not by way of limitation, to a crane structure adapted for installation on a vehicle, or the like, and particularly designed and constructed for change from a stowage position to an operating position with maximum speed and minimum effort.

There are many cranes having folding or jackknife type boom structures available today for mounting on a vehicle, such as that disclosed in the T. S. Holmes Patent No. 2,682,957, issued July 6, 1954, and entitled "Crane With Folding Boom." These presently available devices, however, have many disadvantages. For example, the folding boom members usually constitute a cantilever member in operation wherein bending stresses are transmitted thereto during the lifting of a load. It is well known in the machine design art that a column load is less critical on a supporting member than an equivalent cantilever load. Thus, the utilization of the cantilever boom somewhat limits the load carrying capacities of the apparatus. In addition, the hinge pin connecting the sections of the boom is usually submitted to considerable stress during utilization of the crane, and the limitations thereof greatly reduce the load handling capabilities of the boom. Furthermore, the jackknife booms in use today normally require individual and different types of drive mechanisms for folding of the boom and operation of the crane, which necessitates a multiplicity of components and also increases the time and effort required for moving the boom from the folded or stowage position to the extended or operating position.

The present invention contemplates a novel jackknife type crane structure wherein the geometric construction thereof in the operating position is such that a triangular truss is provided whereby the boom member constitutes a compression member. The stresses in the compression member are similar to those in a column under compressive load, which greatly increases the load handling conditions which may be efficiently achieved with the crane. The sections of the boom are connected in such a manner that the hinge pin functions only as a positioning and retaining member and carries no compression load whatsoever during operation of the crane. The compressive load applied to the uppermost section of the boom is transmitted directly to the lowermost section, thereby utilizing the full cross section of the boom tubing joint. The truss-type construction or configuration places the boom structure in compression as a column, and not in bending as in the case of a cantilevered boom.

The hoisting drum of the novel crane is motor driven through a gear train, and the boom positioning hoist is driven by means of an identical drive mechanism, thus providing for standardization of components. In addition, the boom hoist not only functions for positioning the boom under load, but also serves to manipulate the boom to the folded or jackknifed position for stowage, or over-the-road position. As a result, the crane can be changed from the stowage position to the operating position with great speed and with a minimum of effort on the part of the operator, and in the operating position, maximum utilization of the boom structure is provided with a minimum of parts. This permits a lighter and less expensive structure with optimum utility and speed of operation.

It is an important object of this invention to provide an improved crane wherein the boom member is in compres-

2

sion during operation of the crane for greatly increasing the load handling capacities of the apparatus.

It is another object of this invention to provide an improved crane of the jackknife boom type wherein the hinge pin connecting the sections of the boom is not subjected to compressive loads during the operation of the crane.

Another object of this invention is to provide a novel jackknife type crane particularly designed and constructed to facilitate changing thereof from the folded position to the operating position with maximum speed and minimum effort.

A further object of this invention is to provide a novel crane of the jackknife boom type wherein the maximum utilization of the boom structure is provided with a minimum of components for a light weight construction adapted to portability.

A still further object of this invention is to provide a novel crane which is simple and efficient in operation and economical and durable in construction.

Other and further objects and advantageous features of the present invention will hereinafter more fully appear in connection with a detailed description of the drawings in which:

FIGURE 1 is a side elevational view of a crane structure embodying the invention, and depicting a plurality of positions thereof in dotted lines.

FIGURE 2 is a broken side elevational view of the hinged joint between the boom sections depicting the boom in a folded position.

FIGURE 3 is a perspective view of the hinged joint between the boom sections and depicting the boom in an extended or operating position.

FIGURE 4 is a view taken on line 4—4 of FIGURE 3.

FIGURE 5 is a front elevational view of the upper end portion of the boom.

Referring to the drawings in detail, reference character 10 generally indicates a crane comprising a substantial vertical pedestal member 12 rotatably journaled on suitable base 14 by means of a turn table 16 in any well known manner (not shown). The base 14 may be rigidly secured to the bed of a vehicle (not shown), if desired, but it is to be understood that the crane 10 is not in any manner limited to installation of a vehicle. A section boom member 18 is pivotally secured to the pedestal 12 at 20 in any suitable manner, such as by a pivot pin journaled between a pair of spaced flanges 22, only one of which is indicated in FIGURE 1, and which is depicted broken for purposes of illustration.

The boom 18 comprises an upper section 24 hingedly secured to a lower section 26 for a purpose as will be hereininafter set forth. The lower section 26 is preferably constructed from square tubing, but is not limited thereto, and is provided with a plurality of spaced, outwardly extending apertured flanges 28 at the upper end thereof for receiving a hinge pin 30 therethrough. A pair of substantially identical bracket or guide plate members 32 and 34 (FIGURES 3 and 4) are rigidly secured to the opposed sides of the section 26 in the proximity of the upper end thereof but spaced slightly downwardly therefrom, and extend outwardly in an opposite direction from the flanges 28. A suitable roller 36 is journaled between the bracket or guide plates 32 and 34, and a pair of stanchion members 38 (only one of which is shown) are rigidly secured to opposite sides of the section 26 in the proximity of the plates 32 and 34 for a purpose as will be hereininafter set forth. A pair of oppositely disposed outwardly extending latching pin members 48 (only one of which is shown in FIGURE 1) are provided on the lower section 26 and spaced below the upper end thereof for cooperating with a latching mechanism generally indicated at 50 for securely retaining the section 26 in a substantially upright

t or vertical position when it is desired to fold or jack-
e the boom 18. The latch 50 may be of any suitable
, and is preferably suitably secured to the pedestal
nd connected to a lanyard 52 whereby the latch 50
' be readily manipulated by remote control, as will be
inafter set forth in detail.

he upper section 24 of the boom 18 is also preferably
tructed from square tubing, but not limited thereto,
is provided with a pair of spaced plate members 54
56 rigidly secured to opposite sides of the section 24
extending slightly below the lower end thereof, as
rly shown in FIGURES 2 and 3. The plates 54, 56
substantially identical and may be of any suitable con-
ration whereby the opposite extremities thereof ex-
beyond the opposed faces or sides of the section 24.
left hand portions 58 thereof, as viewed in the draw-
, are spaced slightly outwardly from the hinge flanges
and are apertured for receiving the hinge pin 30
ethrough whereby the upper section 24 is hingedly
red to the lower section 26. The right hand end 60
62 of the plates 54 and 56, respectively, are substan-
y co-planar with the guide plates 32 and 34 and abut
eagainst simultaneously with the abutment of the
ent ends of the sections 24 and 26 in the operating
xtended position of the boom 18. A roller 64 similar
he roller 36 is suitably journaled between the end
ions 60 and 62 for a purpose as will be hereinafter
forth. In addition, a plate member 66 is rigidly sec-
d to the section 24 between the end portions 60 and
and extends below the lower end of the section 24
ibstantial alignment with the lower edge 68 and 70 of
plates 54 and 56 for strengthening of the joint between
sections 24 and 26 in the operating position of the
m 18.

will be apparent that the upper section 24 may be
ted about the hinge pin 30 in order to provide a
knifed or folded position for the boom 18, and as
vn in detail in FIGURE 2. The stop members 38
he lower section 26 are so arranged with respect to
e members 54 and 56 on the upper section 24 whereby
lower edges 68 and 70 of the plates contact the rear
72 of the stop members for limiting the counterclock-
rotation of the section 24, as viewed in the drawings.
; precludes a complete revolution of the upper section
nd provides a substantially horizontal disposition for
upper section 24 in the fully folded or jackknifed
tion of the boom 18, as particularly shown in FIG-
E 1, and as will be hereinafter set forth in detail.

he upper end 74 of the upper section 24 is provided
a plurality of side plate members 76, 77, 78 and 79.
plates 76 and 77 are spaced at one side of the section
and the plates 78 and 79 are spaced at the opposite
of the section 24, as clearly shown in FIGURE 5.
plates are preferably rigidly secured to the end por-
74 by means of a pin or shaft 80 extending there-
ugh and welded thereto. The complementary pairs
lates 76 and 77 are spaced to provide guide plates
support a pair of sheaves 81 and 82 journaled on a
83, and the complementary pairs of plates 78 and 79
spaced to provide guide plates and to support a second
of sheaves 84 and 85, also journaled on the pin 83.
oom cable 88 and a second cable or hoist line 90 are
aded or strung around the sheaves 81, 82, 84 and 85
uch a manner that the resultant loads imposed on the
m 18 are concentrically applied about the longitudinal
er line of the boom.

he boom cable 88 extends from a suitable boom hoist
winch 92 and around the sheave 85 to a suitable cross
ive or block member 94, around the block 94 and
to the sheave 81 to a dead end anchor (not shown)
as normally provided in the proximity of the drum
hoist 92. The hoist cable 90 extends from a hoist or
ch 96 and around the sheave 84 to a suitable hook
k 98, around the hook block 98 and over the sheave
o a dead end anchor (not shown) preferably provided

in the proximity of the drum or winch 96. It will thus
be apparent that stringup is such that both the boom cable
88 and the hoist cable 90 are disposed over sheaves on
each side of the boom 18 for distributing the load evenly
about the center line of the boom. An eye member 100
5 is secured to the outer periphery of the upper boom
section 24, and spaced slightly from the lower end thereof
whereby the hook block 98 may be hooked or secured
therein when it is desired to jackknife the boom 18 for
10 any reason. Of course, the boom hoist 92 and the hoist
or drum 96 are both motor driven through a gear train
(not shown), and are provided with substantially identical
drive mechanisms to provide for standardization of com-
ponents. The boom hoist 92 not only functions for
15 manipulating the boom to the folded or jackknifed position,
but also functions for positioning the boom under
load during the operation position thereof.

As hereinbefore set forth, the latch 50 may be of any
suitable type which may be released by remote control
20 for facilitating operation thereof. As depicted herein,
the latch 50 preferably comprises a pair of spaced link
arms 102 (only one of which is shown in FIGURE 1)
which transversely span the lower section 26, and each
15 having a notch or recess 104 therein for engaging the op-
positely disposed pins 48. The link arms 102 are pivot-
ally secured to the pedestal 12 at 106 whereby they may
25 be pivoted in a direction for release from the engagement
between the notches 104 and pins 48. In order to pivot
the arms 102, a link member 108 may be rigidly secured
30 thereto for receiving the lanyard 52 in order that pres-
sure applied to the lanyard 52 will be suitably transmitted
to the link arms 102 for pivoting thereof in a clockwise
35 direction, as viewed in FIGURE 1. In this manner, the
notches 104 will be lifted from the engagement with the
pins 48 for releasing the lower section 26 of the boom 18.
It is to be noted that release of the pressure on the lan-
yard 52 will permit the latch arms 102 to rotate in a
40 counterclockwise, or reverse direction, and the rotation
thereof is limited whereby a clockwise pivoting of the
lower section 26 will bring the pins 48 into contact with
the latch arms 102 and automatically engage the pins 48
45 in the notches 104 for securing the section 26 in a sub-
stantially vertical position, and for a purpose as will be
hereinafter set forth.

Operation

When it is desired to use the hoist or crane 10 for
manipulation of a load, such as when loading or unloading
50 materials from the bed of a truck, or the like, the
boom 18 is disposed in the extended or operating position
A as shown in solid lines in FIGURE 1. The upper
section 24 is so positioned with respect to the lower sec-
tion 26 that the adjacent ends thereof are in abutting
55 relation. In this manner, a triangular shaped truss is
formed whereby the loads carried by the boom are com-
pressive, and the abutment of the two sections 24 and 26
transmits the compressive force direction to the lower
60 section 26 whereby there is no stress or load on the hinge
pin 30, and the entire cross sectional area of the lower
section 26 may be utilized. The lanyard 52 may be
utilized for releasing the latching engagement between
65 the latch 50 and pins 48, and the entire boom 18 may be
lowered or raised by means of the boom hoist 92 and
boom hoist cable 88 in the usual manner to the desired
working or operating position B as shown in dotted lines
in FIGURE 1. The block hook 98 may be utilized as
is well known for handling the load to be moved or
manipulated.

When the boom 18 is to be folded or jackknifed into
70 a stowage position C, shown in dotted lines in FIGURE
1, the boom hoist 92 and cable 88 are utilized in the
usual manner for elevating or pivoting the boom 18 to
the substantially vertical position A. The clockwise
75 pivoting of the boom 18 about the pivot 20 automatic-
ally engages the pins 48 in the notches 104 for securely

latching the lower section 26 in the substantially vertical position, and precluding rotation thereof in an opposite or counterclockwise direction. The boom hoist 92 is then operated for lowering of the boom 18 whereby the upper section 24 will pivot about the hinge pin 30 in a counterclockwise direction, as viewed in the drawings, to the substantially horizontal position C. The counterclockwise rotation of the upper section 24 is limited by the contact of the plate members 54 and 56 with the stop members 38. The rollers 36 and 64 and guide plates 32 and 34 assure that the hoist line 90 remains on the top or upper side of the boom section 24 in the lowered position thereof, and precludes chafing of the line 90 against any sharp edges, or the like. The hook block 98 may then be secured in the eye member 100 to preclude free swinging of the line when the boom 18 is in the lowered or stowage position. The boom 18 is thus folded or jackknifed into the stowage position until it is desired to use the crane 10 once again.

In order to place the boom 18 in an operation position from the stowage position, the sequence of operation set forth hereinbefore is reversed. The boom hoist 92 is operated for raising the boom whereby the upper section 24 will pivot in a clockwise direction around the hinge pin 30. The section 24 will continue to pivot about the pin 30 until the lower end thereof is brought into contact or abutment with the upper end of the lower section 26. The latch 50 may then be released by actuation of the lanyard 52 for releasing the lower section 26 from the latched position, and the boom 18, in the extended or working position, may be manipulated for handling of the load. Of course, the hook block 98 may be manually released from the engagement with the eye 100 prior to the raising of the section 24, or at any desired time during the raising operation.

It will be apparent that the raising or lowering of the boom 18 to provide alternate working and stowage positions therefor may be accomplished in a minimum of time and with a minimum of effort. The stowage of the boom with the upper section 24 thereof in the substantially horizontal position precludes interference of the boom with the cargo loaded or stowed on the vehicle wherein the crane 10 is mounted. In addition, it is to be noted that the upper section 24 may be lowered either toward the rear of the vehicle, or forwardly toward the cab section since the horizontal section 24 may be disposed either over the cab, or above the bed of the vehicle. Of course, the pedestal 12 is rotatably mounted on the base 14 for complete rotation through an angle of 360 degrees, thus providing no limit to the direction in which the crane 10 may be utilized for handling the load.

From the foregoing, it will be apparent that the present invention provides a novel crane wherein the boom thereof may be folded or jackknifed readily and simply with a minimum of effort, and alternately moved to a working or operation position with equal ease and speed. The boom hoist not only functions for raising and lowering the boom in the working position thereof, but also serves to lower the upper section of the boom to provide the jackknifed position therefor. The triangular truss configuration of the crane is such that the boom member constitutes a compression member wherein increased loads may be efficiently handled thereby. The compressive load in the boom is transmitted directly to the lower section thereof whereby the entire cross section of the boom tubing at the joint may be utilized. In addition, the hinge pin functions only as a positioning and retaining member, and does not carry the compressive load of the boom column. The novel crane device is simple and efficient in operation and economical and durable in construction.

Whereas, the present invention has been described in particular relation to the drawings attached hereto, it should be understood that other and further modifications,

apart from those shown or suggested herein, may be made within the spirit and scope of this invention.

What is claimed is:

1. A crane comprising pedestal means, boom means pivotally secured to the pedestal means, hinge means provided on said boom means to provide alternate positions for stowage and working, means for raising and lowering the boom in the working position thereof,

latch means provided on the pedestal for cooperating with the boom and hinge to provide for folding the boom to the stowage position and maintain the boom in said stowage position independent from any auxiliary equipment, and said last mentioned means also cooperating with the hinge means for raising and lowering the boom from the working position to the stowage position thereof,

and means carried by the boom for limiting the movement thereof during lowering to the stowage position.

2. A crane comprising pedestal means,

boom means pivotally secured to the pedestal means whereby a triangular truss is formed, hinge means provided on said boom means to provide alternate positions for stowage and working, latch means cooperating between the pedestal means and boom means to provide for folding of the boom into the stowage position independently from any auxiliary equipment,

means for raising and lowering the boom while the working position and for raising and lowering the boom from the working position to the stowage position thereof, said last mentioned means being disposed and arranged with respect to the boom to preclude eccentric loading on the boom during operation thereof

said boom in the working position comprising a compression member whereby compression load is precluded from the hinge means, and stop means carried by the boom for limiting the movement thereof during lowering to the stowage position.

3. A crane comprising pedestal means,

sectional boom means pivotally secured to the pedestal means to provide a triangular truss whereby the boom is placed in compression under load during working conditions thereof,

hinge means provided for the boom means to provide for jackknifing thereof, latch means provided on the pedestal means for cooperation with the hinge means and one section of the boom means to provide for jackknifing of the boom independently from any auxiliary support equipment,

means for raising and lowering the boom in the working conditions thereof,

and said last mentioned means also cooperating with the hinge means for alternately changing the boom from the working condition to the jackknifed position thereof, and stop means carried by the boom for limiting the movement thereof during changing thereof to the jackknifed position.

4. In a crane,

pivotal boom means, hinge means provided on the boom means to provide for jackknifing thereof to alternate working positions and stowage positions,

latch means cooperating with the hinge means to provide the jackknifing of the boom means, means provided on the boom means in the proximate of the hinge means for limiting the jackknifing movement in one direction to provide a substantial

horizontal position of one portion of the boom means in the jackknife position, 5
means for pivoting the boom in the working position thereof and cooperating with the hinge means and latch means for jackknifing of the boom means, 10
said boom means comprising a plurality of sections disposed in end to end abutment in the working position thereof to preclude load on the hinge means in the working position of the boom.

A crane comprising
pedestal means,

boom means pivotally secured to the pedestal means and disposed in end to end abutment in a working position of the boom whereby a triangular truss is provided during operation of the boom for placing the boom under compressive loads, 15
means provided on the boom means for providing alternate positions of working and stowage for the boom means,

means carried by the pedestal means and cooperating with the hinge means to provide the stowage position for the boom means independently from any auxiliary support equipment,

means carried by the boom for cooperating between two sections of the boom means for limiting the movement of the boom during lowering thereof into a stowage position,

hoist means for pivoting the boom means during the working position thereof and cooperating with the hinge means and latch means for raising and lowering of the boom to provide the alternate stowage and working positions therefor.

In a crane,
sectional pivotal boom,

means connecting the sections of the boom for alternate positions of extended and jackknifed, 35
means cooperating with the hinge means to provide the jackknifed position of the boom, 40
said sections of said boom disposed in abutting relationship in the extended position of the boom for precluding load on the hinge means during operation of the boom, and means provided on said boom for cooperation between two sections thereof for limiting the movement of one section during jackknifing of the boom for independently maintaining a substantially horizontal position for the said one section in the jackknifed position of the boom.

In a crane,
sectional pivotal boom as set forth in claim 6 wherein hoist means is provided for lowering and raising of the boom in the working position thereof and cooperating with the hinge means for lowering and raising of the boom to and from the jackknifed position thereof, and said hoist means being disposed and arranged with respect to the boom to preclude eccentric loading on the boom during operation thereof.

A crane structure comprising
pedestal means,
boom means pivotally secured to the pedestal means, 60
means securing the boom sections together to provide for jackknifing thereof to alternate working positions and stowage positions,
means carried by the pedestal means for cooperating with the hinge means to provide the jackknifed position for the boom, 65
means provided on the boom means for co-

operating between two sections thereof to limit the movement of one section during jackknifing of the boom to provide a substantially horizontal position for the said one section in the jackknifed position, 70
said boom sections disposed in abutting position in the working position of the boom to preclude any load on the hinge means during operation of the boom,

hoist line means for pivoting of the boom in the working position thereof and for cooperation with the hinge means to provide for the jackknifing of the boom,

and means for retaining the hoist line on the upper side of the boom in the jackknifed position thereof.

9. In a crane,
pivotal boom means,
hinge means provided on the boom means to provide for jackknifing thereof to alternate working and stowage positions,

latch means cooperating with the hinge means to provide said jackknifing of the boom

stop means carried by the boom means for limiting the movement of the boom during jackknifing thereof whereby a portion of the boom will be maintained in a substantially horizontal position in the stowage position thereof,

boom hoisting means for pivoting of the boom means in the working position thereof and for cooperating with the hinge means for jackknifing of the boom means,

load hoisting means cooperating with the boom means for manipulation of a load during operation of the crane,

and means carried by the boom means and cooperating with the boom hoisting means and load hoisting means for distributing the load on the boom means concentrically about the center line thereof during operation of the crane.

10. In a crane,
a sectional boom member,
hinge means connecting the sections of the boom to provide for alternate extended and jackknifed positions therefor,

said boom sections disposed in abutting relationship in the extended position thereof for precluding load on the hinge means during operation of the boom, 45
stop means provided on one section of the boom for limiting rotation of the other section of the boom during the jackknifing thereof,

latch means cooperating with the hinge means for retaining the lowermost section of the boom in a substantially vertical disposition during the jackknifing thereof whereby the jackknifing operation may be accomplished independently of any auxiliary supporting equipment,

means for releasing the latch means in the extended position of the boom,

and hoist means for raising and lowering of the boom in the extended position thereof and for pivoting the uppermost section of the boom during the jackknifing thereof.
